ILLUMINABLE DISPLAY SIGN OR SIMILAR ARTICLE

Conrad J. Escalante, Los Alamitos, Calif.
(1251 W. Gaylord St., Long Beach 13, Calif.)

Filed Nov. 19, 1963, Ser. No. 77,503

Term of patent 14 years

(Cl. D1—12)

FIG. 2.

FIG. 3.

FIG. 4.

FIG. 5.

FIG. 6.

FIGURE 1 is a front perspective view on an illuminable display sign or similar article, embodying my new design, the broken line representation of advertising matter, a support post and brackets being for purposes of illustration only;

FIG. 2 is a rear elevational view thereof;

FIGS. 3 and 4 are elevational views taken from opposite ends thereof, respectively; and

FIGS. 5 and 6 are top and bottom plan views thereof, respectively.

I claim:

The ornamental design for an illuminable display sign, or similar article, substantially as shown and described.
